O. LONDON

WINDOW FIXTURE

Filed June 24, 1921

Inventor

OLIVER LONDON

By N.E. Gee

Attorney

UNITED STATES PATENT OFFICE.

OLIVER LONDON, OF PATON, PENNSYLVANIA.

WINDOW FIXTURE.

Application filed June 24, 1921. Serial No. 480,186.

To all whom it may concern:

Be it known that OLIVER LONDON, a citizen of the United States, residing at Paton, in the county of Cambria and State of 5 Pennsylvania, has invented certain new and useful Improvements in Window Fixtures, of which the following is a specification.

This invention relates to window fixtures of the type adapted to be attached to the 10 window casing without the use of screws, nails or any other similar article all of which deface the casing more or less, and mar the appearance of the wood work around the windows.

15 Another object of this invention is to provide means of attaching the curtain and blind supporting brackets to windows of various widths, as well as windows which are set in thick walled buildings.

20 A further object of this device is to provide means for forcing the bracket carrying means against the sides of the window casing in such manner that the blinds and curtains are firmly held in place.

25 With these and many other objects in view which will be more readily apparent as the nature of the invention is better understood the same consists in the novel construction combination, and arrangement of 30 parts as will be hereinafter fully pointed out illustrated and claimed.

It will be quite readily understood by those skilled in the art to which this invention belongs that the same is susceptible 35 of various changes and modifications without departing from the spirit or scope of the invention, but a preferred and practical embodiment of the invention is shown in the accompanying drawings in which

40 Figure 1 shows a front elevation of my improved curtain fixture, showing the curtain rod and the blind roller carrying means in position.

Figure 2 shows a side elevation of the 45 parts shown in Figure 1 of the drawings.

Figure 3 shows a plan view of the bracket and fixtures as shown in Figure 1.

Figure 4 shows a sectional view of the rod used to secure the curtain fixture bracket 50 to the window casing.

Figure 5 shows an end view of the parts illustrated in Figure 4 of the drawings.

Figure 6 shows side and end views of the window blind roller bracket used in connection with the fixture bracket. 55

Figure 7 shows front and edge views of

the locking means used to lock the window blind roller brackets in position when the blind and roller is assembled in position on the window. 60

Similar reference numerals refer to similar parts throughout the several figures of the drawings.

In carrying out this invention I provide a plurality of brackets designated by the 65 numerals 10 and 11. Each of these brackets is provided with a window casing engaging wing 12, which is made integral with the bracket and adapted to be positioned at right angles thereto. On the face of the 70 wing 12 I provide a dove tailed notch 13 into which fits a member 14 of the angled foot 14^a which is attached firmly to a tubular rod 15, in which is positioned a threaded rod 16, which for the purpose of alignment 75 and adjustment passes through a threaded end 17, of a tubular member 18 to which is attached a hand hold element 19, which is grasped by the one fitting the brackets to a window casing. One of the rods 16 has 80 a right hand thread cut thereon while the one opposite has a left hand thread, otherwise it would not be possible to force the brackets 11 out against the window casing.

From the foregoing it will be apparent 85 that the tubular casing members 17, which are oppositely disposed and carry therewith the angled foot members 14^a, provide a casing or housing for concealing the screw-threaded rods 16, while the manually manipulated expander member 18 has a telescopic 90 fit within the tubular casing members 17 and engages with the screw-threaded rods, thereby providing a novel expander unit 95 for maintaining the brackets 10 and 11 in engagement with the window frame.

The brackets having thus been forced out against the window casing, the blind roller support is then adjusted in length to suit the roller and its end fixtures. The blind roller support consists essentially of a metal casing 20 preferably formed in cross-section like a letter C as shown in Figure 6 of the drawings. Into one of these casings 20 there is fitted a similar casing 21. Each casing is 100 provided with an angled bracket adapted to receive the blind roller end fixtures. The blind roller having been positioned in the fixtures the casings are locked against each other to prevent any longitudinal movement 105 which would necessarily affect the blind roller. 110

The lock designated by the numeral 22, consists of a base plate 23, which is positioned in the inside casing 21, and has attached thereto a cylindrical locking element 24, which is bent in the shape of a letter S, the trunk of the S engaging the edge of the outside casing when the lock is effective. The casings 20 and 21 are each provided with a looped support 25 which is preferably 10 welded to the bracket 11 as shown in Figure 1 of the drawings.

For the purpose of supporting curtain fixtures there are provided adjustable upstanding brackets 27 and 28, which are attached 15 as an integral part of a leg 29 which has a slidable engagement with a bracket 30, positioned on the brackets 10 and 11.

The curtain rod proper is preferably made of tubular casings 31 and 32, one of which 20 is adapted to slide within the other, to suit different widths of windows.

From the foregoing it is thought that the many features and advantages of the invention will be readily apparent without further description, and it will of course be 25

understood that changes in the form, proportion, and minor details of construction may be resorted to without departing from the spirit of the invention or the scope of the appended claim.

30

I claim:

A combined shade and curtain fixture including fixture supporting brackets, and means for forcing said brackets in opposite directions to bind against the sides of the window frames, said means consisting of an expansible locking member including oppositely disposed tubular casing members each having an angled foot member carried therewith and adapted to engage with the brackets, right and left hand screw-threaded rods arranged in and concealed by said oppositely disposed tubular casing members, and a manually manipulated expander member adapted to telescope within the tubular casing members and having threads for engaging with the right and left hand screw-threaded rods.

In testimony whereof I affix my signature.

OLIVER LONDON.
